(57) **CLAIM**

The ornamental design for a shoe, as shown and described.

DESCRIPTION

FIG. 1 is a front, right-side perspective view of a shoe showing our new design.

FIG. 2 is a right-side view of the design shown in FIG. 1.

FIG. 3 is a left-side view of the design shown in FIG. 1.

FIG. 4 is a top view of the design shown in FIG. 1.

FIG. 5 is a bottom view of the design shown in FIG. 1.

FIG. 6 is a front view of the design shown in FIG. 1; and,

FIG. 7 is a rear view of the design shown in FIG. 1.

The short broken lines showing features of the shoe in the drawings form no part of the claimed design.

1 Claim, 7 Drawing Sheets# US D1,087,569 S
